HARRY C. STICKEL, OF STAR JUNCTION, PENNSYLVANIA.

JOURNAL-BOX FOR RAILWAY-CARS.

1,157,446.

Specification of Letters Patent.

Patented Oct. 19, 1915.

Application filed March 24, 1915. Serial No. 16,658.

To all whom it may concern:

Be it known that I, HARRY C. STICKEL, a citizen of the United States, residing at Star Junction, in the county of Fayette and State of Pennsylvania, have invented a new and useful Journal-Box for Railway-Cars, of which the following is a specification.

This invention has reference to journal boxes for railway cars and its object is to 10 provide a box locked to the truck frame in a manner permitting removal of the wheels or replacing brasses without the use of any tools except a lifting jack.

In accordance with the present invention 15 the truck frame is provided with a recess for receiving the journal box, which recess has guiding webs, while the box is formed with interior hollow lugs and guiding ribs serving to hold the box and frame against 20 displacement in any direction except that the frame may be lifted away from the box.

The journal structure is provided with 25 a bearing brass and with a wedge for holding the brass in place and in conjunction with the wedge there is provided a key which when the parts are assembled effectively locks the wedge in place and the latter in turn locks the brass in place, so that the 30 parts retain their proper positions without the presence of bolts or other like fastening devices. In order to remove the wheels or replace the brasses, it is only necessary to lift the truck by means of a suitable jack, 35 whereupon the box is lifted sufficiently so that the wedge can be removed and then the brass and the key may be removed in order. After this the box is in condition for ready removal from the journal end of the axle.

40 The invention will be best understood from a consideration of the following detailed description, taken in connection with the accompanying drawings forming part of this specification, with the further understanding that while the drawings show a 45 practical form of the invention the latter is not confined to any strict conformity with the showing of the drawings, but may be changed and modified so long as such 50 changes and modifications mark no material departure from the salient features of the invention.

In the drawings:—Figure 1 is an elevation of one end of a car truck showing the 55 improvement applied thereto. Fig. 2, is a section on the line 2—2 of Fig. 1, the car

wheel and axle being shown in elevation. Fig. 3 is a section on the line 3—3 of Fig. 2 with some parts shown in elevation. Fig. 4 is an elevation of one end of the truck 60 with the journal box removed. Fig. 5 is a section on the line 5—5 of Fig. 3. Fig. 6 is a side elevation of the box. Fig. 7 is a perspective view of the key. Fig. 8 is a perspective view of the wedge. Fig. 9 is a 65 perspective view of the brass.

Referring to the drawings, there is shown a portion of a car truck frame 1 and there is also shown a car wheel 2 having an axle 3 with the usual journal extension 4.

The truck 1 is indicated as of web and flange construction, but this particular form is not obligatory for the purposes of the present invention. The ends of the truck 1 where provided with journal boxes have 75 each a recess 5 open at the bottom and bordered by flanges 6. These flanges together form a relatively broad bearing face 7 and projecting from the mid point of each face 7 toward the companion face is a 80 web or rib 8 standing upright in the ordinary working position of the parts and located within the space 5. Each web 8 has a rounded lower end 9 and near the upper end has a notch or recess 10.

85 Adapted to the recess 5 is a journal box 11 which in general shape may correspond to ordinary journal boxes for the journals of car wheels. The box 11, however, is provided on opposite faces and the top with parallel ribs 12 spaced to receive between them the flanges 7 and intermediate of the ribs 12, but on the inner faces of the side walls of the box 11, there are formed lugs or housings 13 each with a longitudinal 90 channel shaped to receive a corresponding web 8. Each rib or housing 13 immediately below the top of the box has a passage 14 therethrough matching a corresponding notch 10 in the webbing. The ribs 12 at 95 the sides of the box 11 stop short of the bottom wall of the box and are there joined by a cross rib 12^a which abuts the bottom of the truck frame 1 where formed with the flanges 6. The webs 8 enter the housings or hollow ribs 13 and these housings being open at the upper ends permit the movement of the boxes into the recesses 5 or the movement of the truck frame upon the boxes, as the case may be, and each box is thereby firmly locked to the truck frame 100 against movement in any direction except 105 110

- an up and down direction. There is also provided a brass 14^a such as is customarily employed, this brass engaging the reduced portion 4^a of the journal extension 4 of the axle, such reduced portion being customary in car axles. The brass is formed at one end with an upstanding flange 15 and at the other end with side lugs 16 and the parts are so proportioned that when the brass is applied to the reduced portion 4^a of the journal axle the lugs 16 reach to or approximately to the housings 13 and the flange 15 upstands at the inner or rear portion of the reduced portion of the journal. 10 Applied to the top of the brass is a wedge 17 having a longitudinally outstanding lip 18 at one end. The wedge is of a length to abut at the end remote from the lip 18 against the flange 15, the lip 18 being toward the front end of the journal box 11. 15 The top of the journal box has formed at the front end a depending rib 19 and the extreme front of the box is open as is customary, the bottom wall of the box 20 turning as shown at 20 in the usual manner. The box is provided with the usual hinge lug 21 to which a door or cover 22 is connected by a pintle 23 so as to normally close the front end of the box. 25 When the box is applied to the journal 4 the brass 14^a rests upon the journal, the wedge 17 is applied to the brass, and then between the top of the box and the wedge there is inserted a broad key 24 having a 30 front depending lip 25 adapted to engage over the front edge of the lip 18 of the wedge 17. The key is as wide as or substantially as wide as the interior of the box and is adapted to extend through the passages 14 into channels 26 formed in the hollow lugs or housings 13, which channels receive the webs 8 and the parts are so proportioned that the key then enters the notches 10, thus locking the box to the truck 35 frame 1 through the webs 8. 40 The rear end of the box need not be in one piece with the rest of the box, but can be and preferably is in the form of a plate 27 seated in grooves defined by parallel flanges 28 formed about the rear end of the box within the latter. The plate 27 which constitutes a dust guard has formed through it a suitable passage 29 for the journal end 4 of the car wheel axle. 45 With the structure described the parts when assembled are all in locked relation, the key 24 constituting the locking member and the parts cannot become separated under ordinary conditions of use. 50 When it is desired to replace a brass or to renew the car wheels, or to perform some other such operation, the truck is jacked up, which movement is sufficient to lift the key enough to release the wedge, the wedge 55 and brass remaining in position on the

journal extension 4 without rising with the box. The lifting of the box need be but a short distance before the lip 25 has been raised above the lip end 18 of the wedge 17, whereupon the wedge 17 may be readily removed through the front of the box, when the door 22 has been opened. This provides ample room for the lifting of the brass 14 from the reduced end of the journal 4 and since the parts do not ordinarily make a close fit the key 24 is then readily removed from engaging relation with the notches 10. 70 75

As soon as the key 24 is removed a further lifting of the truck 1 will carry it entirely above the box and the opening 29 being of sufficient size the box is then readily removed from the journal extension 4. 80

When it is not necessary to remove the boxes from the axles, but it is only desired to renew the brasses, the truck may be jacked up as before, so that the key is raised sufficiently to release the wedge, whereupon the latter may be removed, and then the parts taken out and replaced by a new brass, 90 after which the wedge is returned and the parts are once more dropped to the first position where the weight of the car and truck is sufficient to hold the parts in the locked position. 95

The box 11 is when in use supplied with waste 30 for retaining lubricant, this waste being taken as typical of any lubricant carrying material. 100

What is claimed is:—

1. The combination with a car truck having a seat therein, of a journal box adapted to said seat, a brass and wedge adapted to the journal box, and a key adapted to engage the wedge and hold it in the box, said box and truck being coactively formed for the reception of the key to be locked together by said key, with the latter locking the wedge and brass to the journal of a car axle. 105 110

2. The combination with a car truck frame having a seating recess therein with opposed internal webs each with a notch near one end, of a box having internal housings exteriorly channeled to receive the webs, said housings each having a passage and a corresponding web having a corresponding notch, the brass and wedge adapted to the interior of the box and to the journal of a car axle, and a key adapted to the interior of the box and related to the passages through the housings and the notches in the webs of the truck frame to extend through said passages into said notches to lock the box to the truck frame and to lock the wedge and brass to the journal. 115 120

3. The combination with a truck frame and a journal box adapted thereto and provided with a brass and wedge for holding the parts in place, of a key adapted to the 125 130

interior of the box with the said box and the truck coactively formed and the key being also constructed and arranged to lock the box to the truck frame and to lock the 5 wedge and brass to the journal of a car axle.

4. The combination with a car truck having a journal-box receiving recess with opposed interior webs on opposite sides of the recess and the latter opening downwardly 10 in the normal position of the parts, of a journal box having interior housings with exterior channels for receiving the webs, a brass with side lugs for engaging the housings, a wedge provided with a lip at one end 15 and adapted to rest upon the brass, and a key having a lip at one end adapted to engage the lip on the wedge, the housings within the box being provided with passages therethrough and the webs in the recess of the truck frame having notches therein 20 and the key being of a width to extend through the passages in the housings and enter the notches in the webs, whereby the wedge is held to the brass by the key and 25 the box is locked to the truck frame by the key.

5. The combination with a car truck frame and journal box in removable relation to the car truck frame, of journal bearings for 30 the journal of a car axle adapted to the box, and a key for holding the journal bearings in the box to the car axle journal, said key, box and truck frame being coactively constructed and arranged to lock the journal 35 box to the frame.

6. The combination with a car truck frame having a recess with interior opposed upper webs each with a notch near the upper end, of a journal box having interior lugs 40 or housings with exterior channels for receiving the webs of the car truck and said lugs or housings having passages therethrough matching the notches in the webs of the truck frame, said box also having

exterior ribs defining channels for the reception of corresponding portions of the side walls of the recess in the truck frame, a journal brass and wedge adapted to the interior of the box with the wedge provided with a longitudinally extended lip at one 45 end, and a key having an angle lip adapted to engage the lip on the wedge and said key being of a width to extend through the passages in the housings in the box and into the notches in the upright webs in the recess of 50 the truck frame.

7. The combination with a car truck frame having a recess with interior opposed upright webs, each with a notch near the upper end, of a journal box having interior 60 lugs or housings with exterior channels for receiving the webs of the car truck and said lugs or housings having passages therethrough matching the notches in the webs of the truck frame, said box also having 65 exterior ribs defining channels for the reception of corresponding portions of the side walls of the recess in the truck frame, a journal brass and wedge adapted to the interior of the box with the wedge provided with a 70 longitudinally extended lip at one end, and a key having an angle lip adapted to engage the lip on the wedge and said key being of a width to extend through the passages in the housings in the box and into 75 the notches in the upright webs in the recess in the truck frame, the box being also provided with a rib or flange in the path of the lipped end of the key when lodged in the box in locking relation to the parts with 80 which it coacts.

In testimony, that I claim the foregoing as my own, I have hereto affixed my signature in the presence of two witnesses.

HARRY C. STICKEL.
